UNITED STATES PATENT OFFICE.

NICHOLAS J. CONRAD, OF WILMETTE, ILLINOIS, ASSIGNOR TO SCHWEITZER & CONRAD, OF CHICAGO, ILLINOIS, A CORPORATION OF ILLINOIS.

HIGH-TENSION LIQUID BREAK SWITCH.

Application filed June 16, 1924. Serial No. 720,306.

To all whom it may concern:

Be it known that I, NICHOLAS J. CONRAD, a citizen of the United States, residing at Wilmette, in the county of Cook and State of Illinois, have invented a certain new and useful Improvement in High-Tension Liquid Break Switches; of which the following is a full, clear, concise, and exact description, reference being had to the accompanying drawings, forming a part of this specification.

My invention relates to circuit controlling devices, and is designed to provide a device of this character in which the circuit controlling elements are carried by a suitable movable container adapted to occupy alternative positions, the whole structure being so arranged that the open circuit or closed circuit condition of said circuit controlling elements depends upon the particular position occupied by the container. In other words, if the container occupies one position the device is in circuit closing condition, whereas if the container occupies the alternative position the device is in open circuit condition.

The device is designed more particularly for switching purposes in high voltage systems, and in its preferred form the container is provided with an arc extinguishing fluid, to adapt the device for high voltage use. An important feature of the device resides in the provision of circuit controlling elements which move due to the action of gravity from one alternative position to the other, and in the preferred form said elements comprise a plurality of butt contacts, which are connected together so as to move together into and out of circuit closing position, but which are adapted to have a limited relative movement.

The device is also of such a character that it lends itself readily to an increase or decrease of the gap between the contact elements when they are in their open circuit condition. For example, if the device is used for circuits of 2000 to 2400 volts, a comparatively short gap is sufficient, while with a much higher voltage a much larger

gap may be provided by increasing the distance that the contacts travel from closed to open circuit position. The device is of such a character that it can be easily adapted for any size of gap by increasing certain linear dimensions thereof.

Other objects and advantages of the invention will appear as the description of the accompanying drawings proceeds. However, I desire to have it distinctly understood that I do not intend to limit myself to the exact details shown or described, but intend to include as part of my invention all such obvious changes and modifications of parts as would occur to a person skilled in this art and as would fall within the scope of the claims.

In the drawings:

Fig. 1 is a longitudinal sectional view of the container for the switch elements showing one form of switch element therein;

Fig. 2 is a transverse sectional view thereof taken on the line 2—2 of Fig. 1;

Fig. 3 is a side elevation of my improved switching device used as a pole switch;

Fig. 4 is a fragmentary plan view thereof; and

Fig. 5 is an enlarged view in elevation of the movable contact member, the central portion thereof being broken away.

Referring more particularly to the drawings, in Fig. 1 is shown a container comprising a member 20 which is made of insulating material, such as porcelain, and a member 21 of conducting material, said members 20 and 21 together forming a container adapted to contain an arc extinguishing liquid. The members 20 and 21 are mounted on a bracket 22 which is provided with an annular portion 23 having flanges 24 and 25 thereon for receiving respectively the members 21 and 20. The insulating member 20 is secured within the member 25 by any suitable means as by the cement shown at 26. The member 21 is provided with a cap 27 at one end thereof which closes said end permanently, the cap being held in position by means of the pins 28. Said cap 27 is of conducting material, and

is provided with suitable binding posts 29 for securing the conductors 30 thereto.

The member 20 is shown as having corrugations 31 and is provided at the end 5 thereof opposite the bracket 23 with a metallic cap 32 which is provided with a threaded opening for screwthreadedly receiving the disk 33 having a plurality of 10 openings 34 therein. Said disk 33 has a stud 35 mounted centrally therein, which has secured to the inner end thereof the contact plate 36. The member 32 is provided with an ear 37 and with binding posts 38 thereon for securing the conductors 39 to 15 said ear 37.

A contact ring 40 is mounted within the member 21 being held in place therein by means of the rings 41 seated in suitable grooves in the member 21. Thus the ring 20 40 is electrically connected with the casing 21, and thus with the conductors 30, and the contact plate 36 is electrically connected with the cap 32 and thus with the conductors 39.

25 Loosely mounted within the container comprising the members 20 and 21, is a movable contact element comprising a central rod or shaft 42 which is threaded on the ends thereof to receive the bushings 43 and 43'. Said bushings 43 and 43' are each provided with shoulders 44 against which the plates 45 are adapted to rest. The bushings 43 and 43' are also adapted to receive the rings 46 thereon, said rings 46 being 30 spaced from the rings 45 by means of the sleeves 47, and all said members 45, 46 and 47 being held in position on the bushings by means of the nuts 48 and 48' having screwthreaded engagement respectively with 35 the bushings 43 and 43'.

40 Mounted in suitable openings in the rings 45 and 46 provided on the member 43 are contact elements 49, and mounted similarly on the rings 45 and 46 provided on the bushing 43' are the contact elements 49'. Said contact elements 49 and 49' are each provided with a conductor 50 leading to the flanges 51 provided on the members 43 and 43'. The contact elements 49 and 49' are 45 slideable in the openings in the rings 45 and 46, and are each provided with suitable stop members 52 and 53 which are adapted to engage with the ring 46 for limiting the movement of said members 49 and 49' in both directions. The members 49 and 49' normally 50 have a tendency to move in a direction toward the contact members 36 and 40, due to the action of the springs 54 mounted on each of said members between the stop members 53 and the rings 45.

55 The member 22 is mounted in any suitable manner on an insulating member 55, which insulating member is tiltably mounted on a suitable support in a manner simi-

lar to that shown for the insulating members in Figs. 3 and 4 which will be described below.

55 It will be seen that if the device shown in Fig. 1 is in the position shown in said figure the tendency will be for the movable contact means within the container, comprising the members 20 and 21, to move downwardly due to the action of gravity to the position shown for the parts in Fig. 1. Thus the members 49 and 49' will contact with the contact members 36 and 40 and the circuit will be completed through said switching device between the conductors 30 and 39.

60 It will also be seen that if the container is tilted in a direction opposite that shown in Fig. 1 with the conducting portion 21 thereof downwardly inclined below the portion 20, the movable contact means within the container will move toward the end wall 27 and the circuit will be broken due to disengagement with the respective stationary contacts 36 and 40. Although the movable contact member may engage with the conducting casing 21 after such movement has taken place, there will be a long gap between the contacts 49 and the plate 46, the length of the gap being dependent upon the distance which the members 49 are permitted to move away from the contact plate 36, which it will 65 be evident, may be varied as desired in accordance with the requirements of the device by elongating or shortening the members 20 and 21.

65 The container made up of the members 20 and 21 is preferably filled with an arc extinguishing liquid 62, and when the contacts 49 move away from the contact plate 36 the arc resulting therefrom will be extinguished by the arc extinguishing liquid. Gases may 70 form in the container due to the arc, and in order to prevent damage to the container because of the excess pressure, a cap 56 is mounted in the member 32, said cap being merely pressed into position and being 75 adapted to be forced out of position by excess pressure of the gases within the container. In order to assure the closure of the end of the container by the member 56 under normal conditions, holding means for 80 said cap 56 is provided which comprises a strip of frangible material 57, such as thin bakelite which is held in position by means of the screws 58 entering the member 32. It will be evident that upon excess pressure 85 the member 57 will be broken, and the cap 56 will be dislodged to permit relief of said 90 pressure.

95 It will be noted that the ring 40 is provided with a comparatively large opening 59, the member 36 with openings 67, and that the members 45 and 46 are provided respectively with openings 60 and 61 to permit passage of the arc extinguishing fluid 100

62 through the same as the movable contact means within the container is moved from one position to the other position.

The members 43 and 43' are screwthreadedly mounted on the reduced screwthreaded end 63 of the member 42 and are adjustable thereon due to said screwthreads. Positive stop members 64 and 65 adapted to engage the members 36 and 27 respectively are provided on the opposite ends of the member 42. Said stops are screwthreadedly adjustable relative to the member 42 and are locked in adjusted position by the lock nuts 66. Thus any injury to the spring pressed butt contacts 49 and 49' is avoided due to the impact of the member 42 against the members 36 and 27.

In Figs. 3 and 4 a suitable pivotal mounting for a device of this character is shown, 20 said mounting comprising a framework 70 which in the form illustrated is designed for pole top use. The device is illustrated in these figures as designed for outdoor use, and is so arranged that it is weatherproof. 25 The device is adapted for use with a plurality of current controlling devices but only one is shown, although the operating means therefor is adapted for use with more than one, as will be clear from Fig. 4, in which 30 the upper portion thereof is broken away. The containers, which comprise the members 20 and 21 are carried upon the insulators 55 as previously described. The insulators 55 are provided with stems 74 which are secured upon a tube or rod 75 by means of a clamping member 73, which tube or rod has a crank member 76 secured on one end thereof by clamping means 72, the other end thereof being similarly mounted, 40 said crank member 76 connecting the member 75 with the shaft 77. The shaft 77 is mounted in a bearing 78 carried by the framework 70, and has a two-arm bracket 79 provided thereon, which bracket is connected by means of the cords 80 and 81 with the operating handle 82 pivotally mounted on the support 84, which may be carried by the pole or other device which may support the framework 70. Thus when it is 45 desired to change the position of the device 50 from closed circuit to open circuit position, the handle 82 is swung through an arc of substantially 90 degrees, thus swinging the rod 75 through substantially the same arc and swinging the members 71 from the position shown in Fig. 3 to the alternative position with the right hand end thereof upward instead of downward.

The device shown in Fig. 1 is shown reversed from that of the showing in Figs. 3 and 4. In Fig. 1 the container is shown so that the switching means is in closed position when the left hand end thereof is down, while in Fig. 3 the switching means is in

closed position when the right hand end 85 thereof is down. The tube 75 has a further extension 85 which co-operates with two brake elements 86 and 87 suitably held in position by the curved bracket 88. Whenever the device is in either limiting position, the extension 85 co-operates with either the element 86 or the element 87, as the case may be, and these elements act as a brake as the structure is moving into its limiting position, and after the parts have moved into position, said elements act as a holding means to maintain the device in the position into which it was last moved.

In order to include the switching device in circuit, the flexible conducting elements 30 and 39 associate the device with the terminals 89 and 90, respectively, of the circuit. Said terminals 89 and 90 are desirably carried upon insulators 91 mounted on the framework 70 as shown in Figs. 3 and 4.

It will be noted that the tiltable container having the arc extinguishing fluid therein has the insulating portion 20 thereof provided with corrugations and conducting portions 21 thereof plain. As a result, the external appearance of the device is such that it can be readily seen what is the condition of the contacts within the container depending upon whether the corrugated portion is in the position above or below the plain portion thereof. It will also be noted that the flanges 45 and 46 fit loosely within the tubular container or casing, and consequently guide the movements of the movable contact member.

Having thus described my invention, what I desire to claim and secure by United States Letters Patent is:

1. A device of the character described comprising a movable closed container, stationary contacts therein, a plurality of loosely carried solid circuit controlling members therein adapted to occupy either an open-circuit or closed-circuit position depending upon the position of said container, a plurality of said members making a butt contact with each of said stationary contacts and an arc extinguishing fluid within said container.

2. A device of the character described comprising a tiltable container, a stationary contact and contact means within said container shiftable into and out of circuit closing position upon tilting of said container, said means comprising a movable member having a plurality of spring projected contact members mounted thereon cooperating with said stationary contact.

3. A device of the character described comprising a tiltable container, a pair of spaced stationary contacts in said container and shiftable contact means in said container adapted to move into and out of cir-

- 5 cuit-closing position upon tilting of said container, said shiftable means comprising a plurality of contact members making a butt contact with said stationary contacts.
- 5 4. A device of the character described comprising a tiltable container, a pair of spaced stationary contacts in said container and shiftable contact means in said container adapted to move into and out of circuit closing position upon tilting of said container, said shiftable means comprising a plurality of spring projected contact members making a butt contact with said stationary contacts. 70
- 10 5. A device of the character described comprising a tiltable container, a pair of spaced stationary contacts in said container and shiftable contact means in said container adapted to move into and out of circuit-closing position upon tilting of said container, said shiftable means comprising a plurality of contact members making a butt contact with said stationary contacts, said contact members being relatively moveable. 80
- 15 6. A device of the character described comprising a tiltable container, a pair of spaced stationary contacts in said container and shiftable contact means in said container adapted to move into and out of circuit-closing position upon tilting of said container, said shiftable means comprising a plurality of contact members making a butt contact with said stationary contacts, said contact members having a limited relative movement. 90
- 20 7. A device of the character described comprising a tiltable container, a pair of spaced stationary contacts in said container and shiftable contact means in said container adapted to move into and out of circuit closing position upon tilting of said container, said shiftable means comprising a plurality of contact members yieldingly mounted thereon and making a butt contact with said stationary contacts. 95
- 25 8. A device of the character described comprising a closed tiltable container adapted to contain arc-extinguishing liquid therein, a stationary contact therein and contact means within said container shiftable into and out of circuit closing position upon tilting of said container, said means comprising a member having a plurality of similar contact members mounted thereon and a resilient mounting for said contact members whereby said contact members engage substantially simultaneously with said stationary contact. 100
- 30 9. A device of the character described comprising a tiltable container adapted to contain arc-extinguishing liquid therein, a pair of spaced stationary contacts in said container and shiftable contact means in said container adapted to move into and out of circuit closing position upon tilting of said container, said shiftable means comprising a plurality of contact members making a butt contact with said stationary contacts. 105
- 35 10. A device of the character described comprising a tiltable container adapted to contain arc-extinguishing liquid therein, a pair of spaced stationary contacts in said container and shiftable contact means in said container adapted to move into and out of circuit closing position upon tilting of said container, said shiftable means comprising a plurality of individually spring projected contact members making a butt contact with said stationary contacts. 110
- 40 11. A device of the character described comprising a tiltable container, a pair of spaced stationary contacts in said container and shiftable contact means in said container adapted to move into and out of circuit closing position upon tilting of said container, said shiftable means comprising a carrier having a plurality of butt contacts mounted on opposite ends thereof. 115
- 45 12. A device of the character described comprising a tiltable container, a pair of spaced stationary contacts in said container and shiftable contact means in said container adapted to move into and out of circuit closing position upon tilting of said container, said shiftable means comprising a carrier having a plurality of butt contacts yieldingly mounted on opposite ends thereof. 120
- 50 13. A device of the character described comprising a tiltable container, a pair of spaced stationary contacts in said container and shiftable contact means in said container adapted to move into and out of circuit closing position upon tilting of said container, said shiftable means comprising a carrier having guiding means on opposite ends thereof and a plurality of contact pins mounted on said carrier. 110
- 55 14. A device of the character described comprising a tiltable container, a pair of spaced stationary contacts in said container and shiftable contact means in said container adapted to move into and out of circuit closing position upon tilting of said container, said shiftable means comprising a carrier having guiding means on opposite ends thereof and a plurality of contact pins mounted on said carrier at opposite ends thereof. 115
- 60 15. A device of the character described comprising a tiltable container, a pair of spaced stationary contacts in said container and shiftable contact means in said container adapted to move into and out of circuit closing position upon tilting of said container, said shiftable means comprising 125

5 a carrier having guiding means on opposite ends thereof and a plurality of contact pins mounted on said carrier at opposite ends thereof for sliding movement relative thereto.

10 16. A device of the character described comprising a tiltable container, a pair of spaced stationary contacts in said container and shiftable contact means in said container adapted to move into and out of circuit closing position upon tilting of said container, said shiftable means comprising a carrier having guiding means on opposite ends thereof and a plurality of contact pins 15 mounted on said carrier at opposite ends thereof for independent limited sliding movement relative thereto.

20 17. A device of the character described comprising a tiltable container, a pair of spaced stationary contacts in said container and shiftable contact means in said container adapted to move into and out of circuit closing position upon tilting of said container, said shiftable means comprising a carrier having guiding means on opposite ends thereof and a plurality of contact pins mounted on said carrier at opposite ends thereof for independent limited yielding sliding movement relative thereto.

25 18. A device of the character described comprising a tiltable container, a pair of spaced stationary contacts in said container and shiftable contact means in said container adapted to move into and out of circuit closing position upon tilting of said container, said shiftable means comprising a carrier having guiding means on opposite ends thereof, a plurality of contact pins mounted on said carrier at opposite ends thereof for independent limited yielding sliding movement relative thereto and a positive stop for limiting the movement of said carrier in either direction.

30 19. A device of the character described comprising a tiltable container, a pair of spaced stationary contacts in said container and shiftable contact means in said container adapted to move into and out of circuit closing position upon tilting of said container, said shiftable means comprising a carrier having a plurality of butt contacts mounted on opposite ends thereof, said contacts being adjustable relative to said carrier.

35 20. A device of the character described comprising a tiltable container and contact means within said container shiftable into and out of circuit closing position upon tilting said container, said means comprising an elongated body portion having flange-like members on the ends thereof loosely fitting the wall of said container to guide the movements of said means.

40 21. A device of the character described

comprising a tiltable container and contact means within said container shiftable into and out of circuit closing position upon tilting said container, said means comprising an elongated body portion having flange-like members on the ends thereof loosely fitting the wall of said container to guide the movements of said means and contact pins slidably mounted in said flange-like members.

45 22. A device of the character described comprising a tiltable container and contact means within said container shiftable into and out of circuit closing position upon tilting said container, said means comprising an elongated body portion having flange-like members on the ends thereof loosely fitting the wall of said container to guide the movements of said means, contact pins slidably mounted in said flange-like members and resilient means for axially projecting said pins from said flange-like members.

50 23. A device of the character described comprising a tiltable container and contact means within said container shiftable into and out of circuit closing position upon tilting said container, said means comprising an elongated body portion having flange-like members on the ends thereof loosely fitting the wall of said container to guide the movements of said means, contact pins slidably mounted in said flange-like members, resilient means for axially projecting said pins from said flange-like members and stops on said pins engaging certain of said flanges to limit the movement of said pins in either direction.

55 24. A device of the character described comprising a tiltable container and contact means within said container shiftable into and out of circuit closing position upon tilting said container, said means comprising an elongated body portion having flange-like members on the ends thereof loosely fitting the wall of said container to guide the movements of said means and flexible conductors electrically connecting said pins with said carrier.

60 25. A device of the character described comprising a tiltable container having substantially axially aligned sections of conducting and of insulating material, a terminal on each of said sections, a stationary contact member in each of said sections, each electrically connected with the terminal on said section and shiftable means movable into and out of engagement with said contact members upon tilting said container.

65 26. A device of the character described comprising a tiltable container having substantially axially aligned sections of conducting and of insulating material, a terminal on each of said sections, a disk-like stationary contact member in each of said

sections, each electrically connected with the terminal on said section and shiftable means movable into and out of butt engagement with said contact members upon tilting said container.

27. A device of the character described comprising a tiltable container adapted to contain an arc extinguishing liquid, spaced stationary contacts, a shiftable member
10 adapted to bridge the gap between said con-

tacts, said container having an opening in one end thereof, a cap for closing said opening and a frangible strip for holding said cap in closing position whereby said strip is fractured to release said cap when excessive pressure develops in said container. 15

In witness whereof, I hereunto subscribe my name this 10th day of June, A. D. 1924.

NICHOLAS J. CONRAD.
